WATER HEATER

Clarence R. Bernstrom, East Greenwich, R. I.

Application November 9, 1949, Serial No. 126,351

6 Claims. (Cl. 257—229)

1

This invention relates to hot-water systems, particularly for domestic use, and consists in an improved indirect water heater of the so-called tankless type.

One object of the invention is to provide an improved water heater adapted for attachment to any usual type of boiler for furnishing an instantaneous supply of hot water for domestic or other uses.

Another object is to provide a water heater of compact construction comprising a maximum number of heating coils capable of furnishing a continuous supply of hot water without the use of a storage tank.

Another object is to provide a water heater of the type indicated embodying an improved construction of headers for connecting the ends of the multiple coils without requiring separate fittings such as U-bends, elbows, nipples and the like.

Another object is to provide a water heater in which the headers may be constructed as castings requiring only a minimum of machining operations and in which removable separators may be employed as partitioning means for connecting the ends of the coils in series.

Another object is to provide a water heater in which the separators are readily removable for draining the coils.

Another object is to provide a water heater in which the parts may be readily disassembled for cleaning and quickly reassembled to put the heater into condition for use.

Further objects of the invention are set forth in the following specification which describes a preferred form of construction of my improved water heater as illustrated by the accompanying drawings. In the drawings:

Fig. 1 is a part-sectional view of the improved heater taken in the vertical plane of its axis;

Fig. 2 is a plan view of the same with the shell or casing shown in section to illustrate the arrangement of the vertically-disposed spiral heating coils;

Fig. 3 is a view of the upper and lower headers shown in section with the coils partly broken away and illustrating the manner in which the ends of the coils are connected between the headers;

Fig. 4 is a plan view of the lower header; and

Fig. 5 is a perspective view of the partitioning means or separators for insertion into the headers to divide their interiors into compartments for connecting the coils in series.

The present improved water heater comprises

an outer shell or casing 2, preferably of cylindrical form, and made in two half-sections 3 and 4 bolted together at the center to adapt them to be taken apart for cleaning the interior of the casing. As shown in Figs. 1 and 2, the cooperating marginal edges of the semicylindrical sections 3 and 4 of the shell 2 are formed with surrounding flanges 5 and 6 which may be fastened together by a series of bolts 7 and nuts 8 spaced therealong with suitable packing, indicated at 9, inserted between their abutting faces to form a water-tight joint. One half-section 4 of the shell or casing 2 may be formed with flanged openings 10 and 11 interiorly threaded to receive the ends of pipes for connecting the heater to a boiler, the upper opening 10 being constituted as the inlet and the lower opening 11 as the outlet for the boiler water. The opposite half-section 3 of the shell 2 has flanged openings 12 and 13 bored to receive the screw-threaded ends of two parallel tubular headers 14 and 15 which extend horizontally within the interior of the shell 2 at top and bottom thereof. The two headers are of substantially the same construction except that the upper header 14 may be long enough to reach substantially the full distance across the interior of the shell 2 while the lower header 15 is of shorter length.

As one feature of the present improvement the tubular headers 14 and 15 are constructed in the form of castings and provided with lateral openings for receiving the ends of the heating coils, thereby entirely eliminating the use of separate fittings for connecting the coils thereto in series. The upper header 14 is formed at one end with an annular flange 16 and a slightly enlarged threaded extension or nipple 17 for insertion through the opening 12 in the section 3 of the shell 2, see Fig. 1. A nut 18 screwed onto the threaded extension 17 serves to clamp the flange 16 snugly against the interior of the shell-section 3 to rigidly support the header 14 extending horizontally across the interior of the shell 2. The lower header 15 is of the same general construction, having a flange 19 with a threaded extension 20 for insertion through the opening 13 adjacent the bottom of the shell-section 3 with a nut 21 screwed thereonto for securing this element in horizontal position within the shell. Preferably, the interiors of the extensions 17 and 20 are threaded for connecting the headers with the piping system for the hot water supply of a residence or other building.

As shown in Figs. 1 and 2, the heating coils 22 are of helical or spiral form arranged vertically

in nested relationship and connected in series between the two headers 14 and 15. As herein illustrated, a set of five interconnected coils are employed grouped in compact arrangement one within another and spaced at a distance apart to provide for circulation of the heating water between the sides of the coils. Referring more particularly to Fig. 3, the lower header 15 is connected to the domestic hot-water system to provide the intake for the heater through the extension 20. The header 15 is provided with a series of five openings for receiving the terminal portions of the five coils designated *a*, *b*, *c*, *d*, and *e*. The opposite terminal portions of these coils are fitted to similar openings in the side of the upper header 14, the sides of both headers being provided with part-circular bosses 25, as shown in Fig. 4.

Both headers 14 and 15 are formed with axially-extending interior bores 27 and 28, respectively, which may be cored out in the castings and suitably machined to render them straight and true. To connect the ends of the several coils in series with separate paths of flow therebetween the present improvement provides for inserting separators or partitioning means into the bores 27 and 28 of the headers 14 and 15. As has been stated, the bottom header 15 forms the intake for the water to be heated, being connected to the service piping as previously explained. To provide separate paths of flow for the water between the ends of the coils in the header 15 partitioning means or separators 30 are spaced along its interior to divide it into compartments. The separators or partitioning means 30 may be in the form of relatively thin metal disks fitting the bore 28 of the header 15 and fixedly secured to an axially-extending rod 31, the end of which is fastened to a screw-threaded plug 32. The plug 32 terminates in a square nut 33 by which it may be screwed into a threaded opening 34 in the enlarged end of the header 15 with the rod 31 projecting therefrom to maintain the disks 30 in spaced relationship in the header.

The opposite end of the rod 31 may be screw-threaded for connection with a third disk 35 formed with an interiorly-threaded neck 36 for receiving the threads on the rod. The disk 35 is provided with a slot 37 for receiving a screw-driver to screw it onto the end of the rod 31 to fixedly connect it thereto. The disk 35 is provided with a plurality of restricted transverse openings 38 to adapt it to serve as a baffle for controlling the rate of flow of the service water through the heater; the number and size of the openings being subject to variation in accordance with the rate of flow desired. The two partitioning disks 30 and the baffle-disk 35 are so located along the rod 31 that three separate and distinct compartments are formed within the bore 28 of the header 15, see Fig. 3. The first compartment 40 communicates with the intake end of the outer coil *a*; the second compartment 41 communicates with the ends of the two coils *b* and *c* to provide a path of flow therebetween; and the third compartment 42 forms a separate path of flow between the two inner coils *d* and *e*, so that with a similar arrangement of partitioning in the upper header 14 the coils are connected in series.

The coils are connected in series in the upper header 14 in the manner as next explained. Inserted into the bore 27 of the header 14 are two separators or partitioning elements 45 fixedly

secured to an axially-extending rod 46 which is fastened at its end to a plug 47 screw-threaded into the orifice in the enlarged end of the header and provided with a square terminal nut 48. The two partitioning disks 45 thus divide the end of the header 14 into two separate compartments 50 and 51 as shown in Fig. 3. The outer coil *a* and the next inner coil *b* enter the head 14 in communication with the compartment 50 whereby the water from the coil *a* will debouch thereinto and flow therefrom back into coil *b*. On the other hand, the water from coil *c* will debouch into the compartment 51 to flow into the coil *d* while the water from the inner coil *e* will debouch into the remainder of the bore 27 of the header 14, which is not compartmented, so that it will deliver therefrom to the intake end of the hot water system connected thereto.

The outer coil *a* is thus arranged to receive the service water entering the compartment 40 in the header 15, wherefrom it flows through the whole length of this coil (the multiple spiral turns being eliminated from the showing in Fig. 3 for the sake of clarity) and debouches at the end thereof into the compartment 50 at the end of the header 14. The flow of the water is thus continued through the coil *b* back to the header 15 where it debouches into the compartment 41 and thence flows into the end of the coil *c*. The flow continues through coil *c* with the water debouching into the compartment 51 of the header 14 to flow back therefrom through the coil *d* whence it debouches into the compartment 42. From the compartment 42 the water flows into and through the coil *e* to debouch at the end thereof into the bore 27 of the header 14 which is open to its left-hand end. In this way the water will flow through all the coils to enter the service system in heated condition, from which it is supplied to the taps or faucets of the building. The method of operation of the complete water heater is described briefly as follows:

Referring to Fig. 1 of the drawings, the heater is located adjacent the boiler and attached thereto below the low waterline therein. A suitable pipe leading from the boiler is connected to the inlet 10 at the top of the section 4 of the shell 2 and another pipe connected to the outlet 11 at the bottom of the shell for return of the water to the boiler. The heater is connected in the service water supply system by suitable fittings leading to the inlet 13 at the bottom and the outlet 12 at the top of the shell 2. With the boiler water maintained at a temperature of from 180° to 212° F. its heat will be conducted through the copper tubing of the coils within the shell to heat the water flowing therethrough. The water in the service piping flowing through the inlet at the bottom of the heater enters the header 15 with its rate of flow controlled by the baffle disk 35 in accordance with the number and size of the openings 38 therein; it being understood that the rate of flow may be regulated in proportion to the water pressure by substituting baffle disks of different capacities. The water is admitted into the compartment 40 of the header 15 to flow through the outermost coil *a* in the direction indicated by the arrow in Fig. 3. Ascending the coil *a* the water debouches from its end to enter the compartment 46 in the upper header 14, whence it will flow back through the coil *b* to return to the lower header 15. The water debouches from the lower end of the coil *b* into the compartment 41 of the header 15 to enter the coil *c*, ascend therethrough and de-

bouch into the compartment 51 of the upper header 14. The flow is then reversed down through the coil to debouch into the compartment 42 whence it flows into the innermost coil 54 to debouch at its upper end in the bore 21 of the header 14 to feed to the service system in heated condition. In this way a substantially continuous circulation may take place through the several heating coils to raise the temperature of the water to the required degree as it feeds to the service system. The capacity of the heater may be varied in accordance with requirements by increasing the area of the coil surface with a proportionate increase in the size of the shell or casing. With a forced boiler water circulation through the heater its capacity may be increased one-third above its gravity rating.

While the system employed in the present heater is generally similar to those now in use, the present improvement consists in constructional features to render the heater more economical to manufacture with its parts easier and more convenient to assemble while increasing its over-all efficiency. The coils enter the headers in substantially straight courses without the use of separate fittings such as U-bends, elbows and the like, this feature making for economy by eliminating the extra elements and the labor for tapping, threading and installing them. At the same time, the headers are of simple straightforward construction requiring very little machining and with their interiors free from depressions or pockets liable to collect dirt and sediment. Instead of the usual fittings for connecting the outgoing and ingoing ends of the coil pipes a simple arrangement of disk-like spacers or partitioning elements are provided for insertion into the straight bores of the headers to divide the same into compartments. The separators or partitioning disks are held in place by screw-threaded plugs at the end of each header and may be readily and easily removed by unscrewing the plugs so as to open the whole coil system for draining. The spiral coils are of gradual pitch to avoid collecting dirt and sediment therin and in this form they will not develop water hammer. The coil assembly may be readily removed from the shell or casing 2 in unitary connection with the two headers by releasing the nuts on their extensions and separating the two halves of the casing. The coils and the headers form a complete unit assembled without the use of wires, washers, tin strips or the like to hold it together. The rate of flow of water through the coils can be adjusted according to the water pressure by simply substituting different baffle disks with the openings therein varied as required.

It will be observed from the foregoing specification that the present invention provides a particularly simple and compact construction of a tankless water heater capable of being manufactured at low cost yet having maximum efficiency for the purpose intended. While the device is herein illustrated and described in one preferred form, it is to be understood that variations may be made in the shape and arrangement of the parts of the heater without departing from the spirit or scope of the invention as expressed in the following claims. Therefore, without limiting myself in this respect, I claim:

1. In a water heater, a casing having inlet and outlet openings for boiler water, a pair of headers extending across the interior of the casing in spaced-apart relationship and formed with lon-

gitudinally-extending interior chambers for connection with a service water system, a plurality of helical coils arranged in nested relationship within the casing with their ends opening into the interior chambers of the opposite headers, disk-like partitioning elements in the interiors of both headers to divide their chambers into separate compartments for connecting the ends of adjacent coils in series, and means for connecting the partitioning elements in series within the headers to provide for the insertion and removal of each series as a unit.

2. A tankless water heater comprising a two-part sectional casing, means for fastening the sections together to form a water-tight enclosure, inlet and outlet openings in the casing for circulation of boiler water therethrough, a plurality of helical coils disposed vertically in nested arrangement in the casing; a pair of hollow headers extending across the interior of the casing and through its side for connection with a water service system, said headers having lateral openings for receiving the ends of the coils to connect them therebetween, partition elements fitted to the interior of the headers, and means comprising axially-extending rods connecting the partition elements in series for removably holding said partition elements in spaced relationship in the interior of the headers to form compartments connecting the ends of certain of the coils in series.

3. A tankless water heater comprising a two-part sectional casing, means for connecting the sections of the casing to provide a water-tight enclosure, inlet and outlet openings in the casing for circulating boiler water therethrough, a pair of headers each having its end inserted through an opening in the side of the casing and threaded to receive a nut for securing it in place extending horizontally across the interior of the casing, said headers provided with cylindrical bores extending longitudinally thereof and lateral openings communicating therewith, helical coils disposed in vertical nested arrangement in the casing with their terminal portions connected to the lateral openings in the opposite headers, disk-like partitioning elements fitted to the bores in the headers, axially-extending rods for supporting the partitioning elements in spaced relationship within the bores of the headers, and means for fastening the rods at the ends of the headers to hold the partitioning elements in place in the headers.

4. A water heater comprising an outer casing having inlet and outlet openings for boiler water, a pair of headers of tubular construction having means at their ends for securing them in openings in the side of the casing for communication with a service water system, a plurality of helical coils of tubing nested one within another in the interior of the casing with their ends connected to the opposite headers, plugs for closing the open ends of the headers, axial rods supported from said plugs extending longitudinally within the headers, and a plurality of partition elements mounted in spaced relationship on the rods for dividing the interiors of the headers into compartments communicating in series with the ends of the coils.

5. A water heater of the tankless type comprising a casing, headers constructed as castings with longitudinally-extending bores and plural openings in their sides, means for supporting the headers in spaced relationship within the casing extending horizontally across its in-

terior, a plurality of spiral coils disposed in vertical nested arrangement within the interior of the casing with the opposite ends of the coils held in the openings in the sides of the two headers, a plug screw-threaded into the open end of each header and provided with an axial rod projecting from its inner end, partitioning disks secured fast on each rod in spaced relation therewith for dividing the interior of the headers into compartments connecting the ends of the coils in series, and a baffle disk located in the inlet header in connection with the end of the rod and provided with restricted openings for controlling the rate of flow of water into the header and through the coils.

6. In a water heater of the tankless type, the combination of a two-part casing, means for securing the parts of the casing in connection to provide a water-tight interior, inlet and outlet openings in the casing for boiler water, inlet and outlet openings for water from a service system, a header connected at one end to the inlet opening for the service water and extending horizontally partway across the interior of the casing, a second header connected to the outlet opening for the service water and extending substantially the whole distance across the interior of the casing, each header formed as a casting with a longitudinally-extending bore and a plurality of openings in its side, a series of spiral
